UNITED STATES PATENT OFFICE

ESLI A. MARSH, OF CHICAGO, ILLINOIS, ASSIGNOR, BY MESNE ASSIGNMENTS, TO ST. REGIS PAPER COMPANY, OF NEW YORK, N. Y., A CORPORATION OF NEW YORK

FEEDING DEVICE

Application filed March 7, 1929. Serial No. 345,190.

This invention relates to a feeding device and more particularly to a device adapted to fill packages until their contents equals an exactly predetermined weight. The invention relates more particularly to a feeding device in which there is a main feed adapted to feed material rapidly and an auxiliary feeding device adapted to feed material at a lesser rate, and the present invention relates particularly to the arrangement for furnishing material to the auxiliary feeding device. Details and further features of the invention will appear as the description proceeds.

In the accompanying drawings forming a part of this specification, Figure 1 is a front view of apparatus embodying one form of the invention with parts broken away to disclose the construction; Fig. 2 is a view similar to Fig. 1 viewing the device from the left of Fig. 1, parts being broken away and parts in section in order to disclose the construction more clearly.

In the form of invention illustrated, there is a substantially cylindrical propeller casing 10 within which there is a main propeller 11 driven by a shaft 12. Casing 10 is provided with a peripheral opening 13 through which material is discharged into a suitable receptacle.

30 Mounted on casing 10 there is a hopper 14 which supplies the material to impeller 11.

As will be seen, the hopper flares outwardly, and underneath this flaring portion of the hopper and above the line of discharge opening 13 there is arranged an auxiliary propeller 15 adapted to discharge material downward through an opening 16 into passage 13. In the construction shown, the auxiliary propeller 15 comprises a screw driven 40 in a suitable manner from a motor 17 or other suitable power means. Geared to screw 15 to rotate at the same time therewith are agitators 18 and 19 adapted to agitate material and feed it to the screw. The casing 20 of the

45 auxiliary feeder is attached to the side of hopper 14 and is fed through an opening 21 in said hopper. Inside of the hopper there is a guide chute 22, the lower end of which fits into opening 21. The upper end 23 of

50 chute 22 is somewhat smaller than the cross

section of the chute on a level with the upper agitator 19.

The operation of the device is as follows: It will be readily understood that in operating this device, the main part of the charge which is to be filled into a receptacle is discharged rapidly by the main impeller 11. During this time the material is drawn down into the main propeller and moves downward in hopper 14. A part of the stream is intercepted by chute 22 and guided towards the auxiliary feeding device. This auxiliary feeding device may be run or not, as desired, during this portion of the filling operation.

When nearly the desired weight has been discharged into the receptacle, the main impeller is stopped and the auxiliary feeding device continues in operation until the desired charge in the receptacle is completed.

It will be readily understood that when the main impeller is stopped the downward movement of material in hopper 14 is stopped.

With many kinds of material there is a tendency for it to bridge over opening 21 so that the auxiliary feeding device could supply only that in the auxiliary casing while the main impeller was at rest. Chute 22 is introduced to avoid this difficulty. As will be readily apparent this chute becomes filled with material while the main impeller is in operation and the material is moving downward through the hopper. The downwardly flaring construction of chute 22 insures that the material in the chute will flow downward into the auxiliary feeding device even if the material in hopper 14 should bridge over the top of chute 22.

This chute contains an ample supply of material to furnish all that will be needed to complete the charge after the main propeller has been stopped.

It will be readily understood that other types of propellers than those indicated might be used and that the main feed might be stopped by shutting a gate instead of stopping the motion of the impeller and that other obvious changes might be made within the scope of the appended claims.

What I claim is:

1. In combination, a main feeding device,

- a hopper in position to furnish material to said device, an auxiliary feeding device, and a guide chute extending into said hopper, dividing material from that directed towards the main feeding device, and directing said divided material to said auxiliary feeding device. 70
2. In combination, a main feeding device, a hopper in position to furnish material to said device, an auxiliary feeding device, and a guide chute extending into said hopper and directing material to said auxiliary feeding device, said chute expanding towards said auxiliary feeding device. 75
3. In apparatus for charging receptacles, a main feeding device adapted to discharge material rapidly into a receptacle, an auxiliary feeding device adapted to discharge material more slowly into the same receptacle, a hopper in position to supply material to said main device, and a chute extending from said auxiliary device into said hopper, said chute being large enough to enclose as much material as is fed by the auxiliary device 80
- 25 into one receptacle. 85
4. In apparatus for charging receptacles, a main feeding device adapted to discharge material rapidly into a receptacle, an auxiliary feeding device adapted to discharge material more slowly into the same receptacle, a hopper in position to supply material to said main device, and a chute extending from said auxiliary device into said hopper, said chute leading in the same general direction 90
- 35 as the line of travel of the material in said hopper to said main device. 95
5. In apparatus for charging receptacles, a main feeding device adapted to discharge material rapidly into a receptacle, an auxiliary feeding device adapted to discharge material more slowly into the same receptacle, a hopper in position to supply material to said main device, and a chute extending from said auxiliary device into said hopper, said chute leading in the same general direction 100
- 40 as the line of travel of the material in said hopper to said main device. 105
- 45 6. In combination, a cylindrical casing having a peripheral opening, a rotary impeller in said casing adapted to discharge material through said opening, a hopper above the casing and adapted to guide material thereinto, an auxiliary feeding device discharging material in the same direction as said main device, and a chute extending upward into said hopper and leading to said auxiliary device. 110
- 50 7. In combination, a cylindrical casing having a substantially vertical axis, a peripheral discharge opening and a centrally located inlet in its upper end, a main impeller in said casing, an upwardly flaring hopper above said 115
- 55 inlet opening, an auxiliary feeding device dis- 120
- 60
- 65
- 70
- 75
- 80
- 85
- 90
- 95
- 100
- 105
- 110
- 115

- charging material in the same direction as said main device, and a chute extending upward from an opening through the side of said hopper and guiding material to said auxiliary device.
8. In combination, a cylindrical casing having a substantially vertical axis, a peripheral discharge opening and a centrally located inlet in its upper end, a main impeller in said casing, an upwardly flaring hopper above said inlet opening, an auxiliary feeding device discharging material in the same direction as said main device, and a chute extending upward from an opening through the side of said hopper and guiding material to said auxiliary device, said chute expanding downwardly.
- In testimony whereof I have hereunto signed my name to this specification.
- ESLI A. MARSH.
